CARRIAGE REBOUND CHECKING DEVICE

Fred Becker, Queens Village, N. Y., assignor to
Underwood Corporation, New York, N. Y., a corporation of Delaware

Application December 30, 1948, Serial No. 68,322

6 Claims. (Cl. 197—176)

1

This invention relates to the tabulating mechanism of a typewriter and in particular to a rebound check to prevent rebound of the carriage at the end of a tabulating run.

The invention has for one of its objects the provision of a simple, reliable and inexpensive mechanism which will prevent a rebound of the carriage from the tabulator stop at the end of a tabulating run of the carriage.

Another object of the invention is the provision of a carriage rebound checking device which is normally free of the carriage so as to offer no interference thereto and which is brought only momentarily into an active position by the restoration of the carriage tabulating mechanism.

It is also an object of the invention to prevent an incorrect positioning of the typewriter carriage as a result of the rebound of the carriage from a set tabulator stop reed at the end of a tabulating run by means of a rebound latch urged into engagement with the carriage solely by reason of the inertia of the parts of the latch.

Other objects will be in part obvious and in part particularly pointed out in the following detailed description of one embodiment of the invention and in the appended claims.

In the drawings showing one of the possible embodiments of the invention:

Figure 1 is a sectional side view showing the power-operated tabulating mechanism and the rebound check device in their normal positions.

Figure 2 is a rear view of the carriage rebound check device showing the manner of its attachment to the typewriter.

Figure 3 is a top view of the parts shown in Figure 2.

Figure 4 is a detail view from the rear showing the position of the tabulator stop reed of Figure 1.

Figure 5 is a side sectional view showing part of the structure of Figure 1 in the position assumed when the tabulating mechanism is actuated.

Figure 6 is a detail top view showing of a portion of Figure 3 showing the position of the rebound check pawl during a tabulating run as in Figure 5.

Figure 7 is a detail view similar to Figure 4 showing the operated position of the tabulator stop reed.

Figures 8, 9 and 10 are views similar respectively to Figures 5, 6 and 7 but showing the positions of the parts at the end of a tabulating run of the carriage, and

Figure 11 is a perspective view of the rebound checking device.

2

The typewriter to which the invention is applied is the well-known "Underwood Electric" typewriter and for that reason no general description of the machine need be given. The tabulating mechanism disclosed herein is substantially similar to that disclosed in U. S. Patent No. 2,303,878, which issued to W. F. Helmond on December 1, 1942. This mechanism will be only briefly described herein, reference being made to 10 said patent for further details of this well-known structure.

General Description

The typewriter to which the present invention is applied includes a carriage 15 of the usual design freely slideable in grooves 16 in the typewriter frame 23.

15 A spring drum 17 on frame 23 is connected by a flexible tape 18 to carriage 15 to urge the carriage to the left of the operator. A rack 19 on carriage 15 is normally engaged with an

20 escapement controlled pinion 20 on a shaft 46 to restrain the carriage 15 against the drive of spring drum 17 and to permit the normal letter feed movement of carriage 15 during typing operations.

25 A tabulating mechanism is provided to release carriage 15 from the normal restraint of the escapement mechanism and to interpose a stop into the path of carriage 15 to arrest carriage 15 at a new leftward position. This tabulating mechanism comprises, as shown in Figure 1, a tabulating key 21 pivoted on a rod 22 fixed in a frame member 23.

30 An interponent 24, also pivoted on frame member 23, is engaged between the tabulator key 21 and a tabulator action lever 25 to transmit motion from key 21 to lever 25.

35 A hook 26 is slidably and pivotally mounted on lever 25 and is tensioned to be normally in engagement with a lug 27 on a tabulator actuator bar 28. Actuator bar 28 is pivoted at its forward end to a

40 sub-lever 29 carried by the frame 23 and carries near its rear end a pawl 30 which is engageable with a constantly rotating snatch roll 31 by a depression of key 21 acting through the members 24, 25 and 26 to lower the rear end of actuator

45 bar 28. Engagement of pawl 30 and snatch roll 31 will cause an immediate forward stroke of actuator bar 28 which stroke continues until a lug 35 on the rear end of actuator bar 28 is engaged by a tooth of snatch roll 31. Further rotation of snatch roll 31 will elevate the rearward end of bar 28 to disengage pawl 30 from snatch

50 roll 31 and permit a restoring spring 36 to immediately return bar 28 to its normal position as in Figure 1.

55 The forward stroke of actuator bar 28 is com-

municated by an interponent 37 to an arm 38 on a shaft 39 to rock the latter counterclockwise. Another arm 40 on shaft 39 is connected by a link 41 to a lever 42 pivoted near the rear of the typewriter. As more fully disclosed in Patent No. 2,303,878 above mentioned, the carriage 15 and escapement wheel shaft 46 connected thereto by pinion 20 and rack 19 are, upon operation of shaft 39 and lever 42, freed from the restraint of a conventional escapement mechanism, not shown in detail, by a lever 47 connected between the forward end of lever 42 and a part of the escapement mechanism. Counterclockwise rocking of lever 42 also projects the upper end of a tabulator reed 48 connected by a pivot pin 65 to the rear end of lever 42 into the path traveled by a set one of the settable tabulator stops 49 on the rear of carriage 15. The tabulator stops are vertically slideable in the usual tabulator rail 50 and are downwardly settable to an effective position by a manually operated finger 51 in the usual manner.

Shaft 39, lever 42 and tabulator reed 48 are retained in their operated positions by a latch lug 52 fixed near the top end of reed 48 which lug 52 is, in the operated position of reed 48, raised above a plate 53 fixed to the upper part of the tabulator reed housing 55, see Figures 2 and 7, and drawn, as shown in Figure 7, into latching engagement therewith by a spring 54 connected between the reed 48 and a part of the housing 55. Actuator bar 28 is free to be returned to its normal position by its restoring spring 36 despite the latching of shaft 39 and its connected parts in their actuated positions, by reason of the pin and slot connection between actuator 28 and interponent 37.

The latched parts are released from their actuated positions by the engagement of a set carriage stop 49 with the upper end of tabulator reed 48. Such engagement will move the upper end of reed 48 to the right, Figure 10, and thereby move lug 52 from engagement with plate 53 to free reed 48 to the action of a reed restoring spring 56 connected between the reed 48 and the lower part of the housing 55. Reed 48 in its return to normal position, restores levers 47, 42 and shaft 39 to their rest positions, as shown in Figure 1, lever 47 concurrently reengaging the escapement mechanism to restrain the carriage 15 in its adjusted position.

Tabulator rebound check

A tabulating mechanism of the type above described does not under certain conditions always position the paper carriage at the desired position since the resilience of the carriage stop 49 and tabulator reed 48 may, particularly in arresting the carriage 15 after a long carriage run, throw the carriage in a reverse direction for a distance of several letter spaces. Since the tabulator reed 48 is released from latch plate 52 when the carriage 15 is first arrested and immediately reengages the escapement mechanism pawls with the escapement wheel, the carriage 15 after such a rebound, stops in a position one or more letter spaces to the right of the intended position.

The novel mechanism of the present disclosure has been devised to prevent an incorrect tabulation due to such rebound of the carriage from the tabulator reed 48. The rebound check is free of the carriage 15 at all times except immediately after a tabulation when it is moved to momentarily engage a stop 49 on the tabulator rack 50. The rebound check device is pivotally

mounted on a bracket 59, Figure 2, fixed to the rear of the tabulator housing 55. The rebound check comprises a U-shaped frame 60 pivoted to the ends of bracket 59 by screws 61. The lower bar of frame 60 is flanged downwardly, see also Figure 11, and has secured thereto an arm 62 to which is fixed a weight 63, the weight 63 being carried rearwardly of the vertical plane through the pivots 61 and tending to rotate the frame 60 clockwise about its pivots 61. Adjustably secured to the forward end of arm 62 is a nose 64 which will, in the normal position of the parts, be pressed by the action of weight 63 against the pin 65 forming the connection between lever 42 and tabulator stop reed 48.

The left arm of frame 60 is extended upwardly and formed into a stop nose 66, Figure 11, which may be engaged with the top of the unset tabulator stop 49 to the left, Figure 3, of the set stop 49 which engages tabulator stop reed 48. A support 67 for stop nose 66, Figure 2, is adjustably secured to a bracket 68 extending from the tabulator housing 55 and is positioned to the left of stop nose 66 with a clearance sufficient to permit frame 60 to oscillate freely about its pivots 61.

Carriage rebound check operation

It is believed that the operation of the rebound check will be clear from the above description and only a brief summary of the functions will be set out here. Prior to initiation of a tabulating operation, the parts involved are in their normal positions as shown in Figures 1, 3 and 4. In these positions tabulator stop reed 48 is down below the path of any set stops 49 on the carriage 15, shaft 39 is in its clockwise position, and nose 64 of the rebound check 60 rests against pin 65 of the stop reed 48, thus positioning the stop nose 66 as in Figure 3, i. e. slightly to the right and rear of a tabulator stop 49. Nose 66 is also very slightly to the left of its support 67 (right in Figure 2). In these positions, the carriage 15 is free to be moved without interference. Upon operation of a tabulator key 21, actuator bar 28 is, as set out above, driven to the left to rock shaft 39 counterclockwise and, through link 41 and lever 42, to project stop reed 48 to its upper position wherein its end is positioned to intercept a set one of the tabulator stops 49. Lug 52 of stop reed 48 is drawn to the left by spring 54 to snap over plate 53, see Figure 7, and hold the stop reed 48 projected. Projection of reed 48 will move pin 65 from in front of nose 64 of the rebound check 60, thereby allowing the weight 63 to rock the rebound check 60 clockwise to the position shown in Figure 5. A suitably positioned stop 69 may be provided to engage the check frame 60 and so limit forward movement of nose 64 to the desired extent. Such clockwise rocking of the rebound check 60 moves its stop nose 66 to the position shown in Figure 6, that is, more to the rear of the line of tabulator stops 49 than in the normal rest position.

At the end of a tabulating run of the carriage 15, a set stop 49 thereon engages the upper end of stop reed 48 and moves it to the left, right in Figure 10, to displace lug 52 from above plate 53 and free stop reed 48 to the restoring action of its spring 56. The resulting downward movement of stop reed 48 immediately reengages the escapement mechanism to prevent further leftward movement of the carriage 15 after stop reed 48 has dropped below the path of stop

49. The abrupt termination of the carriage movement and the natural resilience of the tabulator stop 49 and stop reed 48 tend at this time to impel the carriage 15 back to the right. However, the lowering of stop reed 48 causes its pin 65 to strike the upper part of nose 64 of the rebound check 60, see Figure 8, and rock the check 60 counterclockwise, the inertia of weight 63 carrying the check 60 through its normal Figure 1 position into the position shown in Figure 8. At this time, the stop nose 66 has entered into the path of the tabulator stops 49 as in Figure 9. The rebound of the carriage 15 from stop reed 48 now engages stop 49 with nose 66 and distorts the extended arm 60 carrying stop nose 66 until the arm 60 engages the fixed support 67 and prevents further reverse movement of carriage 15. As the total rebound movement of carriage 15 under these conditions is limited to less than one letter space, it is evident that carriage 15 will be arrested before rebounding out of the proper letter space and spring drum 17 will then urge carriage 15 into the desired tabulated position.

When the carriage 15 is arrested after a long tabulating run by the structure as described above, it may happen that carriage 15 will rebound a second time. The rebound check 60 will strike pin 65 with its nose 64 and rebound to an effective position only slightly less than the original position shown in Figure 8. By a proper selection of the mass of weight 63 and the clearance of stop nose 66 from stops 49 in the rest position, the time required for the rebound of check 60 may be made the same as the time interval between the first and second carriage rebounds and the stop nose 66 will then be effective to halt the second rebound of carriage 15.

After the carriage has settled in its new position, the rebound check 60 comes to rest in the position shown in Figure 1 wherein it is out of the path of travel of carriage 15.

As many changes may be made in the specific mechanism as detailed above without departing from the spirit or scope of the invention, it is to be understood that the above description is not to be taken in a limiting sense, the invention to be limited only by the following claims.

What is claimed is:

1. In a typewriter of the like having a movable carriage, means to urge said carriage in one direction, a releasable escapement mechanism to normally restrain said carriage from movement, and tabulating mechanism settable to release said escapement mechanism to free said carriage and to position a stop into the path of a part of said carriage to thereby arrest said carriage at a selected position, said tabulating mechanism being restorable by said carriage at said selected position, a normally ineffective rebound check device to momentarily engage said carriage and prevent reverse movement of said carriage from said selected position, means on said tabulating mechanism operable during restoration of said tabulating mechanism to impel said rebound check device toward effective position, and an inertia means on said rebound check device to impel said device fully into effective position, said inertia means normally acting to maintain said check device in engagement with said tabulating mechanism impelling means wherein said rebound check device is clear of said carriage.

2. In a typewriter having a carriage, settable tabulating mechanism to control tabulation of

said carriage to a given position, normally ineffective means to momentarily prevent reverse movement of said carriage from said given position, means to restore said tabulating mechanism to an ineffective position, means operated by said tabulating mechanism during said restoring movement to drive said reverse movement preventing means partially to its effective position and an inertia member on said reverse movement preventing means to carry said means into its fully effective position.

3. In a typewriter having a carriage and tabulating mechanism therefor, said tabulating mechanism being manually controlled for movement into an effective position and restorable under control of said carriage, means engageable with said carriage to prevent a rebound of said carriage after completion of a tabulating movement thereof, said means comprising a pivoted bail, a carriage engaging tooth extending from one arm of said bail, and an inertia member and a driving nose on the crosspiece of said bail, and means on said tabulating mechanism normally engaging the driving nose of said bail, said bail being urged to position said driving nose into the return path of said means on said tabulating mechanism when said tabulating mechanism is set into effective position whereby said means on said tabulating mechanism in its return movement strikes said driving nose of said bail and restores it to normal position, the inertia of said bail and said inertia member thereupon causing said bail to move further in the restoring direction to momentarily engage said carriage engaging tooth with said carriage.

4. In a typewriter having a carriage and tabulating mechanism therefor, said tabulating mechanism being manually controlled for movement into an effective position and restorable under control of said carriage, means engageable with said carriage to prevent a rebound of said carriage after completion of a tabulating movement thereof, said means comprising a pivoted bail, a carriage engaging tooth extending from one arm of said bail, and an inertia member and a driving nose on the crosspiece of said bail, means on said tabulating mechanism normally engaging the driving nose of said bail, said bail being urged to position said driving nose into the return path of said means on said tabulating mechanism when said tabulating mechanism is set into effective position whereby said means on said tabulating mechanism in its return movement strikes said driving nose of said bail and restores it to its normal position, the inertia of said bail and said inertia member thereupon causing said bail to move further in the restoring direction to momentarily engage said carriage engaging tooth with said carriage, and a support positioned adjacent said carriage engaging tooth to prevent excessive flexing of said tooth under the impact of said carriage during rebound.

5. A typewriter having a carriage, means to urge said carriage in one direction, a releasable escapement mechanism to restrain said carriage against the urge of said urging means, a tabulating mechanism settable under manual control to release said carriage from said escapement mechanism and including a stop member positionable in the path of said carriage, said tabulating mechanism being restorable to withdraw said stop member and reengage said escapement mechanism by engagement of said carriage and said stop member whereby said car-

riage is subjected to forces tending to drive it in a rebounding direction, a rebound preventing means normally clear of said carriage, means on said tabulating mechanism stop member and operative in the return movement of said stop member to engage said rebound preventing means and drive it toward an effective position, and an inertia member on said rebound preventing means to impel said preventing means into a fully effective carriage intercepting position and then return said preventing means to a normal ineffective position in engagement with said means on said tabulating mechanism stop member.

6. In a typewriter having a carriage, tabulating mechanism therefor including a projectable stop, stops on said carriage settable into a position cooperable with said projectable stop, a rebound preventing stop normally free of said carriage stops, means connected with said rebound preventing stop to engage a part of said projectable stop and means on said rebound preventing stop to impositively urge said connected means in a direction to engage said connected means with said part of said projectable stop, said tabulating mechanism and projectable stop being settable under manual control to an effective position and

10

5 restorable to normal position under control of said carriage whereby said part of said projectable stop is first moved out of engagement with said means connected to said rebound preventing stop, said connected means thereupon moving into the return path of said part of said projectable stop, and thereafter engages said connected means to drive said rebound preventing stop to normal position, said rebound preventing stop being free to then move further to engage said rebound preventing stop with one of the upset stops on said carriage, and a support member adjacent said rebound preventing stop to arrest said carriage without an excessive flexure of said stop.
